UNITED STATES PATENT OFFICE

2,436,871

CENTER FREQUENCY STABILIZED FREQUENCY MODULATED OSCILLATOR

Karl Rath, New York, N. Y., assignor to Radio Patents Corporation, New York, N. Y., a corporation of New York

Application February 24, 1944, Serial No. 523,633

4 Claims. (Cl. 179—171.5)

1

My invention relates to high frequency oscillators of the type embodying a piezo-electric crystal as a stabilizing means to obtain a substantially constant oscillating frequency.

Crystal controlled oscillators known in the art utilize the crystal as an effective element of the oscillating circuit whereby the crystal forms an integral part of the oscillating mechanism. Arrangements of this type have various disadvantages such as due to excessive heating of the crystal causing variations of its resonant frequency and other characteristics and requiring a thermostatic control and other means to maintain the crystal at constant operating temperature.

Another disadvantage is the fact that a crystal controlled oscillator cannot be directly frequency modulated, which necessitates the use of phase modulation and other means to overcome this drawback. Furthermore, due to the extremely high "Q"

$$\left(\frac{wL}{R} \right)$$

of the crystal, the starting or building up of the oscillations in many cases is not sufficiently smooth to enable rapid keying and to suit other purposes and requirements.

Accordingly, an object of my invention is to provide a single tube crystal controlled oscillator, wherein the crystal is arranged outside the oscillating circuit proper and serves merely as a stabilizing means for the oscillations generated independently of the crystal.

Another object is the provision of a single tube high frequency oscillator circuit of the regenerative or feedback type comprising a tuned oscillating circuit the frequency of which may be controlled in any desirable manner and a piezo-electric crystal element associated with the same tube or circuit and serving for stabilizing the oscillations or maintaining the carrier or center frequency of the oscillations at a substantially constant value.

These and further objects and advantages of my invention will become more apparent from the following detailed description taken in reference to the accompanying drawing forming part of this specification and wherein:

Figure 1 shows an oscillator circuit embodying a piezo-electric crystal as a frequency control or stabilizing element in accordance with the principles of the invention; Figures 2 and 3 are graphs explanatory of the function and operation of the circuit according to Figure 1; Figure 4 shows a

2

modification of a single tube oscillator according to the invention, and Figure 5 illustrates a complete frequency modulated oscillator embodying a center frequency stabilized oscillator according to the invention.

Like reference numerals identify like parts throughout the different views of the drawing.

Referring more particularly to Figure 1, I have shown at 10 an electronic discharge tube comprising a heater element 11, a cathode 12, an inner control grid 13, an accelerating or screen grid 14, an outer control grid 15 and an anode or plate 16, all substantially arranged in the order named. A resonant oscillator or tank circuit 17 is connected to the inner control grid 13 and ground or cathode and coupled with the accelerating grid 14 also known as an anode grid through a feedback coil 18 and blocking condenser 19. A condenser-shunted resistance 20 is inserted in the common cathode return lead for the control grid and screen grid circuits to provide proper grid operating bias potential in a manner well understood. The screen grid 14 is connected to the positive pole of a suitable high tension or space current supply source indicated by the plus symbol in series with a load resistance 21.

The circuit connected to the cathode 12 and grids 13 and 14 constitutes a standard regenerative feedback oscillator capable of generating an oscillating frequency determined by the resonant frequency of the tank circuit 17. Any other oscillator circuit known in the art and operatively associated with the cathode 12 and grids 13 and 14 may be employed for the purpose of this invention, as will be readily understood. In order to stabilize the oscillating frequency, I have shown a piezo-electric crystal 22 connected between the outer control grid 15 and ground and shunted by a high impedance element previous to direct current such as a choke coil or high ohmic resistance 23 as shown in the drawing. The plate 16 is connected to the positive pole of the space current supply source and by-passed to ground for high frequency current by a condenser 24. The oscillations generated are applied to a suitable output or utilization circuit connected to terminals 0—0 by way of a coupling condenser 25 or in any other manner known and well understood.

It will be noted that the crystal 22 is connected in a circuit remote or substantially decoupled from the oscillator circuit proper and accordingly will not be subject to the drawbacks and defects of known oscillator circuits, wherein the crystal forms an effective element or part of the oscilla-

tor circuit. The function of the frequency stabilization in a circuit of the type shown in Figure 1 will be further understood from the following:

Electrons passing from the cathode 12 to the screen or accelerating grid 14 and subjected to a fluctuation in accordance with the oscillating frequency, will in part pass through the meshes of the grid 14 and be attracted and collected by the anode or plate 16. In passing from the screen 14 to the plate 16, the electrons will be decelerated due to the effect of the negative electric field surrounding the outer control grid 15 being at ground potential or having a potential negative with respect to ground due to the action of the biasing resistance 20.

As a result of this decelerating action, a dense electron cloud or concentrated space charge also known as a virtual cathode will be formed adjacent to the grid 15, said space charge having a charge density which varies in accordance with the oscillating frequency determined by the resonant frequency of the tank circuit 17. As a result of this variable space charge, an oscillating current will be induced by electrostatic induction in the outer circuit connected to the grid 15 and cathode 12 and including the crystal 22. The phase of the induced current depends on the character of the impedance offered by the crystal and accordingly, will be dependent upon the relative frequency departure between the oscillating frequency and the fixed resonating frequency of the crystal.

If, under normal conditions, the oscillating frequency or resonant frequency of the tank circuit 17 corresponds to the resonant frequency of the crystal 22, the induced current passing through the crystal will be exactly 90° out of phase with the oscillating frequency due to the fact that for this frequency the crystal offers pure resistive impedance and that the induced current varies in accordance with the rate of change or derivative of the space charge fluctuations which latter are in phase with the oscillating frequency. If the oscillating frequency deviates in either sense from the resonating frequency of the crystal 22, the impedance offered by the crystal to the induced current will become either capacitative or inductive, resulting in a phase shift of the potential of grid 15 being greater or smaller, as the case may be, than the normal 90° or quadrature phase relation. Accordingly, the potential upon the grid 15 caused by the drop of the induced current through the crystal will have a phase with respect to the phase of the potential on the grid 13 determined by the oscillations, which varies both in sense and magnitude depending on the departure of the oscillating frequency from the resonating frequency of the crystal 22.

As a result of the dual control of the electron stream passing to the plate 16 by the potentials on the grids 13 and 15 of varying relative phase, the average or steady plate or output current varies in a manner shown by the curve i_a in Figure 2 as a function of the frequency f of the oscillations, i. e. in turn the resonant frequency of the tank circuit 17. In case of equality between the resonating frequencies of the tank circuit 17 and the crystal 22 the average plate current has a value I_0 equal to the plate current if one of the grids 13 or 15 were omitted or disconnected, i. e. determined solely by the steady operating and bias potentials of the tube. This condition corresponds to a normal operating frequency identified as f_0 in Figure 2. If the oscil-

lating frequency increases or decreases with respect to this normal value, the steady or direct plate current i_a varies substantially linearly within a given operating range in either direction from the point P corresponding to the normal plate current I_0 . The average or steady current passing to the screen grid 14 undergoes a similar change as shown by the dotted line curve i_{sg} , that is, with the phase or sense of the variations reversed with respect to those of the anode current i_a .

According to the present invention, the average plate or screen current changes as a function of an initial deviation of the oscillating frequency from its desired or normal value f_0 determined by the resonating frequency of the crystal 22, are utilized to effect a frequency control to counteract the initial frequency deviation in a manner to restore the original or normal oscillating frequency. In the embodiment of the invention shown in Figure 1, there is inserted for this purpose in the screen grid circuit a load impedance in the form of an ohmic resistance 21 of suitable resistance value to produce a potential drop by the screen grid current i_{sg} causing a variation of the steady screen grid potential. The latter reacts upon the tank circuit 17 to vary the reflected reactance thereof in such a manner as to maintain a constant oscillating frequency independent of drift and other causes tending to vary the resonating frequency of the tank circuit 17. This function will be further understood from the following.

It is well known in vacuum tube circuits of this type that a reactance, usually a capacitative reactance, is reflected from the plate to the grid due to inter-electrode coupling (Miller effect), which reflected reactance is proportional to the output potential i. e. in the present case to the operating potential of the screen grid 14. Since the latter varies in accordance with the deviations of the oscillating frequency from the predetermined resonating frequency of the crystal 22, the variations of the reflected reactance, by the proper design of the circuit constants and parameters, will be such as to compensate for or counteract an initial frequency variation in a manner to restore and maintain a substantially constant oscillating frequency.

The reactance reflected into the grid or tank circuit 17 usually of a capacitative nature, in some cases may be of an inductive type and may vary in either sense in proportion to the potential on the screen grid 14. In order to obtain the proper phase of the reflected reactance variations to counteract the initial changes of the oscillating frequency, various methods may be utilized depending on the particular oscillating circuit employed. Thus, in Figure 4 there is shown a circuit wherein the operating potential for the screen grid 14 serving as output electrode for the oscillator is derived from the plate current i_a , having a phase opposite to the screen current changes as shown in Figure 2. Alternatively, the crystal 22 may be utilized at either its parallel-resonant or its series-resonant frequency, in which case again the plate and screen current changes will be reversed. Figure 2 corresponds to the operation of the crystal at its parallel-resonant frequency, while Figure 3 shows the plate and screen currents if the crystal 22 is employed at its series-resonance. In the latter case, as is seen, the phase of the plate and screen current changes is reversed. By using the proper method of operating the crystal or utilizing

ing either screen grid or plate current changes for producing the operating potential for the screen 14, it will be possible to provide a screen grid potential varying in the proper sense as a result of an initial deviation of the oscillating frequency from its assigned value, whereby to counteract said deviation and to restore and maintain a constant oscillating frequency.

Referring to Figure 4, there is shown a circuit similar to Figure 1 with a somewhat different oscillator circuit connected to the cathode 12 and grids 13 and 14. This oscillator differs from Figure 1 in that the oscillating or tank circuit 17 is connected to the screen 14 and the feedback coil 18 is connected to the control grid 13 in connection with a coupling condenser 27 and grid leak resistance 28. The plate circuit in this case includes a load impedance 30 to produce a plate potential varying in accordance with the relative frequency departure of the oscillating frequency from the assigned frequency of the crystal 22 as shown by the curve i_a in Figures 2 and 3, depending on whether the crystal is utilized at its parallel-resonant or at its series-resonant frequency, respectively. The varying plate potential serves for energizing the screen grid or output electrode 14 of the oscillator, whereby to control the reflected reactance appearing in the grid circuit and affecting the resonant frequency of the tank circuit 17 by virtue of the inductive coupling between the latter and the grid circuit.

Referring to Figure 5 I have shown a center frequency stabilized oscillator similar to Figure 1 associated with a separate reactance control tube 35 for controlling the oscillating frequency in accordance with the variations of a signal source such as a microphone or the like to obtain a frequency modulated oscillation having a substantially constant center or carrier frequency and an instantaneous frequency varying in proportion to the signal current variations.

There is connected for this purpose in parallel to the oscillator tank circuit 17 a reactance control tube 35 comprising a heater 36, a cathode 37, a control grid 38, a screen grid 40, a suppressor grid 41 and an anode 42. The control grid 38 is excited by a quadrature potential derived from the oscillating circuit by way of a phase shift network comprising a resistance 44 and a condenser 45 and connected across the tank circuit through a large blocking condenser 43. The screen grid 40 and anode 42 of the control tube are connected to a suitable space current supply source by way of potential drop resistors 46 and 47, respectively. The control grid 38 is furthermore excited by a signal potential by way of an audio transformer 50 having a primary connected to a battery 51 and a microphone or other signal device 52.

The function of the control tube 35 is well known. By varying the control potential in accordance with the signals a variable reactance represented by the cathode-anode path of the tube is connected across the tank circuit 17, resulting in a corresponding variation or modulation of the oscillating frequency. In order to prevent potential variations of the anode 16 in accordance with the signal frequencies from being impressed upon the grid 14, a choke coil 31 is inserted between the grid 14 and the load resistance 30 in the anode circuit of the oscillator. In this manner, only slow variations of the oscillating frequency due to drift and other causes will be impressed upon the screen grid 14 and neutralized by the compensating or fre-

quency control action in the manner described. If desirable, the choke coil 31 or an equivalent filter or impedance device may be designed to admit of a certain amount of the signal frequency variations for the purpose of obtaining an inverse feedback effect in addition to the center frequency control for the purpose of improving the linearity of the modulation, reducing noise and obtaining other advantages of inverse feedback well known.

From the foregoing and the diagrams shown in Figures 2 and 3, it is found, in the case of the standard triode oscillator associated with the electrodes 12, 13 and 14 wherein the reflected reactance in the grid circuit is of a capacitative nature in accordance with the well-known Miller effect, that in order to counteract an initial oscillator frequency deviation from the crystal frequency, the crystal should be operated at series resonance when utilizing the screen grid current to produce the frequency responsive oscillator anode voltage upon grid 13 such as shown in Figure 1, and that the crystal should be operated at parallel-resonance when utilizing the plate current to produce the varying oscillating anode potential, as shown in Figure 5. This will be further understood from the following.

The reflected or Miller capacity may be considered as a hypothetical variable condenser connected in parallel to the condenser of the tank circuit 17, thus determining the oscillating frequency. The capacitance of this Miller condenser is proportional to the oscillator anode potential, that is, the potential upon the screen grid 14. Thus, assuming that the oscillator frequency f tends to increase, the hypothetical Miller condenser should also increase in order to counteract this tendency by reducing the oscillating frequency. This in turn necessitates an increase of the oscillator anode potential upon grid 14 or, in other words, a decrease of the anode and screen current, whichever is used for producing the frequency-responsive oscillator anode potential.

Hence, if the crystal is operated at its parallel-resonant frequency, corresponding to Figure 2, it will be the anode current i_a which decreases with increasing oscillating frequency f , while if the crystal is operated at its series-resonant frequency, corresponding to Figure 3, it will be the screen grid current i_{sg} which decreases with increasing oscillating frequency.

Accordingly, in the case of Figure 1 where the varying screen current is used to control the oscillator anode potential, the crystal 22 should be operated at its series-resonant frequency, while in the case of Figure 5 where the varying anode current is used to control the oscillator anode potential, the crystal should be operated at its parallel-resonant frequency in order to counteract the initial oscillator frequency deviations and to stabilize the oscillator.

Since both parallel- and series-resonant frequencies of a crystal are closely adjacent to each other, it may be easily determined, by experiment and from the relationship shown in Figures 2 and 3, which operating mode should be chosen for a given oscillator circuit and a given relation between the reflected reactance and the anode operating voltage.

It will be evident from the foregoing that the invention is not limited to the specific circuits, arrangements of parts and details shown and disclosed herein for illustration, but that the underlying thought and principle are susceptible

of numerous modifications and variations coming within the broader scope and spirit of the invention as defined in the appended claims. The specification and drawing are accordingly to be regarded in an illustrative rather than in a limiting sense.

I claim:

1. An oscillator comprising an electron discharge tube having a cathode, a first control grid, a screen grid, a second control grid and an anode, all arranged substantially in the order named, a regenerative oscillating circuit comprising a resonant tank circuit connected between said first grid and said cathode and feedback coupling means therebetween and said screen grid to generate sustained electrical oscillations having a frequency determined by the resonant frequency of said tank circuit, a piezo-electric crystal shunted by a high impedance previous to direct current and connected between said second control grid and said cathode, said second control grid having a steady bias to produce a concentrated electron space charge adjacent thereto and fluctuating at oscillating frequency, whereby to cause the steady electron current to vary in sense and magnitude in proportion to relative frequency departure between the generated oscillations and the resonant frequency of said crystal, a load resistance connected to said anode, means for applying varying operating potential to said screen grid from said load resistance to thereby control the reactance reflected upon said tank circuit and to vary the oscillating frequency to counteract initial deviations thereof from the crystal frequency, means to modulate the frequency of the generated oscillations in accordance with a modulating signal amplitude, and means in the screen grid circuit to prevent anode current variations in accordance with the modulating signal frequency from affecting the steady potential of said screen grid.

2. An oscillator comprising an electron discharge tube having a cathode, a first control grid, a screen grid, a second control grid and an anode, all arranged substantially in the order named, a regenerative oscillating system comprising a resonant tank circuit connected between said first control grid and said cathode and feedback means therebetween and said screen grid to generate sustained oscillations having a frequency determined by the resonant frequency of said tank circuit, a piezo-electric crystal shunted by a high impedance previous to direct current and connected between said second control grid and said cathode, a load resistance connected to said anode, a conductive circuit connection from said anode to said screen grid for applying varying operating potential thereto, an output circuit connected to said tank circuit, further means for controlling the frequency of the generated oscillations in accordance with a modulating signal, and means in the screen grid circuit to substantially prevent anode current variations in accordance with said modulating signal from affecting the screen grid potential.

3. An oscillator comprising an electron discharge tube having a cathode, a first control grid, a screen grid, a second control grid and an anode, all arranged substantially in the order named, a regenerative oscillating system comprising a resonant tank circuit connected between said first control grid and said cathode and feedback means therebetween and said screen grid to generate sustained oscillations having a frequency determined by the resonant frequency of said tank circuit, a piezo-electric crystal shunted by a high ohmic resistance and connected between said second control grid and said cathode, a load resistance connected to said anode, and means for applying varying operating potential to said screen grid from said load resistance, an output circuit connected to said tank circuit, further means for controlling the frequency of the generated oscillations in accordance with a modulating signal, and audio frequency choke means inserted in the screen grid circuit to substantially prevent anode current variations in accordance with said modulating signal from affecting the screen grid potential.
4. An oscillator comprising an electron discharge tube having a cathode, a first control grid, a screen grid, a second control grid, and an anode, all arranged substantially in the order named, a regenerative oscillating system comprising a resonant tank circuit and connected between said first control grid and said cathode, and feedback coupling means therebetween and said screen grid to generate sustained electrical oscillations having a frequency determined by the resonant frequency of said tank circuit, a piezo-electric crystal shunted by a high impedance previous to direct current and connected between said second control grid and said cathode, a load resistance connected to said anode, means for applying varying operating potential to said screen grid from said load resistance, further means for controlling the frequency of the generated oscillations in accordance with a modulating signal, an output circuit connected to said tank circuit, and means in the screen grid circuit to prevent anode current variations in accordance with said modulating signal from affecting the screen grid potential.
